UNITED STATES PATENT OFFICE

DANA C. DAY, OF LOS ANGELES, CALIFORNIA, ASSIGNOR TO MONICAL MANUFACTURING COMPANY, OF LOS ANGELES, CALIFORNIA, A CORPORATION OF NEVADA

FLASH LIGHT

Application filed November 21, 1928. Serial No. 320,905.

My invention relates to a flashlight of the particular type disclosed in my copending application for Letters Patent filed October 3, 1928, Serial Number 310,098, and the principal object of my present invention is to generally improve upon and simplify the construction of the flashlight disclosed in my aforesaid patent application, as well as other existing forms of similar flashlights.

Further objects of my invention are to provide a relatively simple, practical and inexpensive flashlight that is designed to be worn on the forehead, thereby enabling the wearer of the lamp to utilize both hands in manipulating tools or working on parts that are illuminated by said lamp, further to provide improved means whereby the lamp housing is mounted for universal adjustment upon the base plate or supporting member, and further to provide a flashlight of the character referred to that comprises relatively few parts that are capable of being readily manufactured, and assembled to produce the complete structure.

With the foregoing and other objects in view, my invention consists in certain novel features of construction and arrangement of parts that will hereinafter be more fully described and claimed and illustrated in the accompanying drawing, in which:

Fig. 1 is a vertical section taken through the center of a flashlight constructed in accordance with my invention.

Fig. 2 is a cross section taken on the line 2-2 of Fig. 1.

Fig. 3 is a rear elevational view of the flashlight and showing the base plate applied to the forehead of the wearer and which supports the adjustable lamp housing.

Fig. 4 is a plan view of the flashlight and showing the means for supporting the same on the forehead of the user.

Fig. 5 is a perspective view of a frame that is utilized for supporting the lamp carrying disk and its socket within the lamp housing.

Referring by numerals to the accompanying drawings which illustrate a practical embodiment of my invention, 10 designates a plate, preferably formed of thin metal such as aluminum, and which is curved slightly

lengthwise in order to fit comfortably upon the forehead of the wearer, and formed in the ends of this plate are slots 11 for the reception of a tape 12, preferably elastic, that passes around the head of the wearer, thereby firmly holding the plate 10 in position on the forehead. 55

Secured in any suitable manner to the front face of plate 10 is a socket 13 within which is mounted a hemispherical member 14. This member 14 is mounted to move within the socket and to hold the same firmly after movement, an expansive spring 15 is positioned between the socket and member 14. 60

Projecting outwardly from the center of the member 14 is a threaded stud 16 that serves as a point of connection for the lamp housing 17. This lamp housing is preferably formed of thin sheet metal, substantially 70 hemi-ovoid in shape and provided on its forward end with a thread 18 that makes one complete turn.

Adapted to engage the thread in the forward end of the lamp housing is the threaded 75 portion of a collar or bezel 19 that carries a concave reflector 20 and a lens 21.

Arranged within the rear portion of the lamp housing 17 is a bow-shaped strap or frame 22 of thin metal, the ends of which are 80 turned inwardly toward each other and secured to said ends in any suitable manner is a disk 23 of insulation and the edge thereof fits snugly against the inner face of the lamp housing. 85

To clamp the frame 22 within the lamp housing, and to support the latter on the adjustable member 14, threaded stud 16 projects through coinciding openings formed in the lamp housing and frame, and mounted 90 on the inner end of said stud is a nut 24.

Threaded stud 16 passes through the lamp housing 17 and frame 22 at a point a short distance below the axis of the lamp housing, and as a result of this arrangement said housing when in its normal position and with the plate 10 in proper position upon the forehead, occupies a position slightly above said plate 10, thereby positioning the lamp within said housing a substantial distance above the 100

eyes of the user. Further, such mounting of the lamp housing permits a greater range of adjustability of the lamp housing.

Positioned on the stud between the lamp housing and the member 14 is a spacing collar 25.

Secured to the rear face of disk 23 is a centrally arranged metal disk 26 and formed integral therewith is a threaded socket 27 that projects through an opening in the center of disk 23, and said socket receives the threaded plug portion of a small electric lamp 28, the bulb of which projects through a centrally arranged opening in the reflector 20.

Secured to the rear face of the disk 23 is one end of a contact spring 29, the free end thereof occupying a position directly behind the threaded socket 27 so as to be engaged by the contact of the plug of lamp 28 when said plug is screwed into the socket 27.

Leading from a suitable source of electric current supply, preferably a battery 30, are conductors 31 in which is located a suitable switch 32, and one of said conductors is connected to contact spring 29 and the other conductor is connected to the disk 26.

The battery 30 and switch 32 are preferably of the type contained in a small housing or case that may be conveniently carried in the pocket or attached to the clothing of the user of the lamp.

In the use of my improved flashlight plate 10 is positioned on the forehead of the wearer with the elastic band 12 encircling the head and the lamp housing supported upon said plate 10 may now be shifted into any desired position so as to direct the rays of the lamp onto the work that is being done or onto the tools that are being manipulated by the hands of the wearer of the lamp.

The universal joint between the plate 10 and lamp housing enables the latter to be easily and quickly swung into various positions and the pressure exerted by the expansive spring 15 firmly holds the lamp housing in its adjusted position.

The frame 22 provides a firm and substantial support for the disk 23 that carries the lamp socket 27, and said frame is firmly secured within the lamp housing by tightening nut 24 on the threaded shank 16, thus greatly facilitating the assembly of the parts associated with the lamp housing.

A flashlight of my improved construction may be advantageously employed as a trouble light while making adjustments and repairs upon automobiles, airplanes, motor boats or in fact any work that may be accomplished to better advantage when illuminated with light rays, and said lamp may also be used to advantage by physicians, dentists, oculists or other persons engaged in like professions.

Likewise the lamp may be used by persons

traveling or driving at night and by persons engaged in mining or other underground work.

Thus it will be seen that I have provided a flashlight to be worn upon the forehead, thereby enabling the wearer to freely use both hands in the manipulation of tools for accomplishing the various kinds of work, and which flashlight is relatively simple in construction, inexpensive of manufacture, and capable of being easily and quickly adjusted to suit different conditions.

It will be understood that minor changes in the size, form and construction of the various parts of my improved flashlight may be made and substituted for those herein shown and described without departing from the spirit of my invention, the scope of which is set forth in the appended claim.

I claim as my invention:

In a flashlight, a plate adapted to be positioned upon the forehead of the wearer, a socket arranged on the upper central portion of the front face of said plate, a lamp housing, a stud projecting downwardly and rearwardly from the rear portion of said housing at a point below the axis thereof, a hemispherical member carried by said stud and arranged within said socket the outer portion of which hemispherical member is provided with a recess and an expansive spring arranged within said recess and bearing against said hemispherical member.

In testimony whereof I affix my signature.

DANA C. DAY.
